EXTENSION DEVICE

Willard A. Davis, Edgewood, R. I., assignor, by
mesne assignments, to Gemex Company, a cor-
poration of New Jersey

Application January 30, 1935, Serial No. 4,099

8 Claims. (Cl. 24—71)

My present invention relates to the jewelry art, and has particular reference to extension devices suitable for bracelets and watch chains.

Extension devices heretofore used have included a plurality of members foldable into contracted relation, and have occasionally included a ratchet mechanism to provide closer length adjustment. The ratchet mechanism has either been an integral part of the extension device, whereby the ratchet parts are engaged when the extension device is in folded relation, and are not engaged when the extension device is opened to extended position, or has been independently operated, as by means of manually operable levers or pressure members.

The first arrangement has the disadvantage that any definite length adjustment cannot be automatically retained, the over-all length being adjusted after each closing of the extension device. It is a principal object of my invention to provide a construction which maintains any selected length adjustment and does not require resetting.

The second arrangement, while possessing constant setting, has heretofore required lateral movements of releasing mechanism to release the ratchet parts, the releasing mechanism being difficult to operate, and particularly when the bracelets are small, and being relatively unsightly in appearance. It is a further object of my invention to provide a releasing mechanism that does not require lateral operating movements, and that does not change the general appearance of the extension device or of the bracelet.

It is an additional object of my invention to provide a novel construction whereby the extension device may be opened when in folded position, to either release the foldable parts and retain the ratchet parts in cooperative set position, or to simultaneously release both the foldable parts and the ratchet parts.

With the above and other objects and advantageous features in view, my invention consists of a novel arrangement of parts more fully disclosed in the detailed description following, in conjunction with the accompanying drawing, and more specifically defined in the claims appended thereto.

In the drawing,

Fig. 1 is a plan view of an extension device embodying the novel invention;

Fig. 2 is a side elevation of Fig. 1, the foldable parts being in opened relation;

Fig. 3 is an enlarged bottom plan view of the extension device in open position, parts being broken away;

Fig. 4 is a section on the line 4—4 of Fig. 3;

Fig. 5 is an enlarged view of the ratchet parts, in extended relation;

REISSUED

MAR 18 1941

Fig. 6 is an enlarged section on the line 6—6 of Fig. 1; and

Fig. 7 is a perspective of one construction suitable for the ratchet pawl.

I have found it desirable to provide an extension device with a ratchet mechanism which is controlled by the user to permit opening and closing of the foldable parts without change in the ratchet mechanism, to permit change in the ratchet parts at any time whether the foldable parts are in open or closed relation, and to permit simultaneous release of the foldable parts from closed relation and of the cooperating ratchet parts. To this end, I have provided a finger tab which may be moved to open the foldable parts, and which may be further moved to release the ratchet parts, the structure being designed to be inconspicuous and without lateral projections, levers, knobs, or the like.

Referring to the drawing, the extension device 10 is adapted to be utilized as part of a bracelet or a watch chain, and includes a top plate 11, an intermediate plate 12 hinged to one end thereof, and a base plate 13 hinged to the intermediate plate, the base plate having the usual end connection 14 for securing to one end of a bracelet. An adjusting link 15 is slidably mounted in the top plate, between the rolled edges 16, 17 thereof, and has an end formation 18 for hinged connecting to the other bracelet end. The base plate 13 has spaced laterally projecting catch elements 19 adapted to engage the ends of the rolled edges when the plates are folded between the rolled edges, for detachable securing of the parts in contracted relation.

As indicated in Figs. 3 and 4, the adjusting link has a plurality of central openings or detents 20 at the inner end thereof, the outer end being cut to simulate the general appearance of a bracelet or watch chain link, and is held against removal from the top plate in any desired manner, as by forming a stop 21 in the top plate to engage the inner part of the adjusting link. A pawl 22, see Fig. 7, is mounted in the top plate, and includes a spring tongue 23 having a rearwardly bent tooth 24 selectively engageable with the detents 20, sides 25 which have yieldable spring fingers 26 frictionally engaging the rolled edges 16 and 17, and arcuate portion 27 which rests on the hinge 28 between the top plate and the intermediate plate, and functions as a fulcrum, and a finger piece 29 which extends past the edge 30 of the top plate. Although the described construction of the pawl locks it in place in the top plate, the part 27 may if desired be formed as a hinge and mounted on a pivot pin secured in the sides 16, 17. All the parts are preferably made of stamped metal.

The operation of the novel extension device may now be explained. When the parts are in the

relation shown in Fig. 4, the foldable plates are in contracted relation and the adjusting link and pawl are in shortest length adjustment. An opening contact of the finger piece by a finger nail, 5 the bracelet or watch strap being on the wrist, releases the catches 18 from engagement with the ends of the top plate edges, and opens the foldable plates to extended position; the ratchet parts are not released, however, and the length 10 adjustment remains as set. If, however, the finger piece be pressed further against the edge of the top plate, the pawl will turn on the hinge 28, as indicated by the dotted lines in Fig. 4, and release the ratchet mechanism. A slight opening 15 movement of the finger piece thus releases the foldable parts, and a stronger movement releases the ratchet parts. When the ratchet parts are released, and slide apart as indicated in Fig. 5, the adjusting link may be ratcheted inwardly, whether the foldable parts are in extended 20 or in contracted relation.

While I have described a specific constructional embodiment of my invention, it is obvious that desired changes in the size and material of the 25 parts, in the relative arrangement and in the relative functioning, may be made to suit the requirements for different bracelets and watch chains, within the spirit and the scope of the invention as defined in the appended claims.

30 I claim:

1. In an extension device, a member, a second member slidably connected thereto, cooperating length adjusting elements on said members, a third member hingedly connected to one of said 35 other members and adapted to fold in contracted relation thereto, cooperating snap elements on said third member and one of said other members for releasably retaining said third member in contracted relation thereto, and manually movable 40 means for releasing said snap elements and simultaneously moving one of said cooperating length adjusting elements to disengage the same.

2. In an extension device, a member, a second member slidably connected thereto, cooperating length adjusting elements on said members, a third member hingedly connected to one of said other members and adapted to fold in contracted 45 relation thereto, cooperating snap elements on said third member and one of said other members for releasably retaining said third member in contracted relation thereto, and manually movable 50 means for releasing said snap elements and for simultaneously moving one of said cooperating length adjusting elements to disengage the same, said manually movable means being positioned at 55 one end of said first member.

3. In an extension device, a plate, and an adjusting link slidably connected thereto at one end thereof, said plate and link having cooperating pawl and ratchet elements, the element associated with said plate being pivotally mounted in said plate, and having a manually engageable part extending outwardly from the other end of the plate.

4. In an extension device, a plate, an adjusting link slidably connected thereto at one end thereof, said link having a series of detents, and a pawl element pivotally mounted in said plate and having a finger selectively engageable with said detents, and having a manually engageable part extending outwardly from the other end of the plate, a second plate hingedly connected to said first plate and contractable in folded relation

therewith, and cooperating releasable catch and latch parts on said plates, said manually engageable part contacting said first plate to disengage said cooperating catch and latch parts upon movement thereof. 5

5. In an extension device, a plate, an adjusting link slidably connected thereto for extension from one end thereof, a plate element, said link and plate element having cooperating pawl and detent means, the plate element being mounted for 10 swinging movement in said plate, and having a manually engageable part extending outwardly from the other end of the plate. 15

6. An extensible buckle comprising, in combination, a housing link having opposed longitudinal wall portions, a sliding link member mounted in said housing link between said wall portions for sliding longitudinal movement relative thereto, a control member pivotally anchored to said housing link and movable transversely 20 only with respect to the longitudinal dimensions thereof, and a finger piece on one end of said control member extending from one end of said housing link between the planes of said wall portions for operating said control member, one of said members having a series of ratchet teeth along a portion of its length and the other of said members having a pawl thereon, said pawl and said ratchet teeth being juxtaposed within 25 said housing link so that transverse movement of said finger piece relative to said housing link separates said pawl and said ratchet teeth, whereby said sliding link member is freely slidable in said housing link. 30

7. An extensible buckle for a bracelet or the like, comprising, in combination, a housing link having opposed longitudinal wall portions, a sliding link member mounted in said housing link between said wall portions for sliding longitudinal movement relative thereto, a control member anchored within said housing link and movable vertically only with respect to the plane thereof, a finger piece secured to said control member and extending from one end of said housing link between the planes of said wall portions, one of said members having a series of ratchet teeth formed along a portion of its length and the other of said members having a pawl formed thereon, said pawl and said ratchet teeth being juxtaposed within 40 said housing link so that vertical movement of said finger piece outwardly of said bracelet separates said pawl and said ratchet teeth whereby said sliding link member is freely slidable in 45 said housing link. 60

8. An extensible buckle comprising, in combination, a link, a sliding link member mounted on said link for sliding longitudinal movement relative thereto, a control member anchored to said link and movable transversely only with respect to the longitudinal dimensions of said link, and a finger piece on one end of said control member extending from one end of said link for operating said control member, one of said members having a series of ratchet teeth along a portion of its length and the other of said members having a pawl thereon, said pawl and said ratchet teeth being in juxtaposed relation upon said link 65 so that transverse movement of said finger piece relative to said link separates said pawl and said ratchet teeth, whereby said sliding link member is freely slidably on said link. 70
